CLAIM

The ornamental design for an accessory mount, as shown and described.

DESCRIPTION

FIG. 1 is left front isometric view of an accessory mount according to my new design;

FIG. 2 is a left rear isometric view of the accessory mount shown in FIG. 1;

FIG. 3 is a front view of the accessory mount shown in FIG. 1;

FIG. 4 is a rear view of the accessory mount shown in FIG. 1;

FIG. 5 is a top view of the accessory mount shown in FIG. 1;

FIG. 6 is a bottom view of the accessory mount shown in FIG. 1;

FIG. 7 is a left side view of the accessory mount shown in FIG. 1; and,

FIG. 8 is a right side view of the accessory mount shown in FIG. 1.

The broken lines show portions of the accessory mount that form no part of the claimed design.

1 Claim, 6 Drawing Sheets
